(57) **CLAIM**

The ornamental design for pad for fixed vehicle GPS, as shown and described.

DESCRIPTION

FIG. 1 is a perspective view of pad for fixed vehicle GPS showing my present design,

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view; and,

FIG. 8 is a perspective view of pad for fixed vehicle GPS.

In the drawings, the broken lines shown in FIG. 8 depict a GPS and form no part of the claimed design.
